UNITED STATES PATENT OFFICE.

THOMAS WALDRON, OF COLUMBUS, OHIO.

DISPENSING CARTON.

Application filed May 26, 1922. Serial No. 563,952.

My invention relates to improvements in dispensing cartons, and is especially directed to cartons constructed of paper board and having pouring spouts.

My object is to provide a carton, made of a single piece of material which is so cut and scored as to be formed into substantially rectangular shape, and provided with integral elements which seal the contents and which may be cut for the discharge of the contents, through a pouring spout, and employed, until the carton is completely emptied, as a closure, between times of pouring or discharging.

My improvements consist in the novel construction, arrangement and combination of elements as hereinafter fully, clearly and concisely set forth, definitely pointed out in my claims and illustrated by the accompanying drawings, in which:

Figure 1 is a plan of the blank out of which my carton is formed.

Figure 2 is a plan of the carton, as folded and with both its ends open.

Figure 3 is a side elevation of the carton, folded sectionally, as in Figure 2 and with both ends open.

Figure 4 is a side elevation of the carton opposed to Figure 3, showing the lower end closed and the upper end open for filling.

Figure 5 is a plan of the carton in closed and sealed condition and showing by dotted line the cutting line for opening the carton to expose its pouring spout.

Figure 6 is a vertical sectional elevation of the fully closed carton, taken on the line indicated 6—6 of Figure 5.

Figure 7 is a perspective view showing the carton as opened for pouring or discharging, and

Figure 8 is a transverse vertical sectional elevation of the carton taken on the line indicated 8—8 of Figure 6 showing the pouring spout in closed or non-discharging position and the sealing flap or closure in open position.

Referring by alphabetical symbols and numerals to the drawings, A designates the carton proper, B a pouring spout, and C a sealing flap.

As recited the entire carton, including its pouring spout and sealing flap is made of a single piece of material, as shown by the blank in Figure 1, in which the parts 10 and 11 constitute the sides of the carton; the parts 12 and 13 the ends of the carton;

the parts 14, 15, 16 and 17 the bottom of the carton; the parts 18, 19 and 20 the top of the carton; the parts 21, 22 and 23 the pouring spout B; the parts 24 and 25 the sealing flap C, and the part 13^a a lap for joining the side and end walls sectionally.

As shown in Figure 1, the side 10, is defined in the contour of the blank, at its one margin, while its remaining margins are defined by the scored lines 26, 27 and 28, and the side 11 is defined by the scored lines 29, 30, 31 and 32.

The end 12 is defined by the scored lines 33 and 34 and by the recited lines 26 and 29, and the end 13 is defined by the lines 35 and 36, by the recited line 30 and by a scored line 37.

The bottom part 14 has two of its margins defined in the contour of the blank, and of its remaining margins, the one is defined by the recited line 28 and the other by a cut line 38.

Another bottom part 15 has its one margin defined in the contour of the blank, another margin defined by the recited line 32 and its remaining margins defined by the cut lines 39 and 40.

A third bottom part 16, has its one margin defined in the contour of the blank and its remaining margins defined by the scored line 34 and cut lines 38 and 39, and the fourth bottom part 17, has two of its margins defined in the contour of the blank and its remaining margins defined by the scored line 36 and cut line 40.

The one part 18 of the top has two of its margins defined in the contour of the blank, a margin defined by the recited line 27 and its remaining margin defined by the cut line 41; a second part 19 of the top has two of its margins defined in the contour of the blank, a margin defined by the recited line 31 and its remaining margin defined by the cut line 42, and the third part 20 of the top has one whole margin defined in the contour of the blank; portions of two other margins defined in the contour of the blank, the remaining of the last two mentioned margins being defined by the recited cut lines 41 and 42 and its fourth margin defined by the recited scored line 33.

The pouring spout, is defined by the recited line 35, cut lines 43 and 44 and by the contour of the blank.

In forming the carton from the blank, the sides 10, 11 and ends 12, 13 are folded

on the lines 26, 29, 30, 37, to rectangular shape, sectionally, as shown in Figure 2 and the lap 13^a secured as by gluing.

The bottom is then folded and formed by 5 first bending the parts 16 and 17 along the lines 34 and 36, to stand at right angles to the ends 12 and 13; the parts 14 and 15 are then bent along the lines 28 and 32 at right angles to the sides 10 and 11 and all 10 of the bottom parts relatively secured as by gluing.

The formed carton is then ready for filling in its contents, after which the top part 19 is first folded along the line 31 to 15 stand at right angles to the end 12; in which position it will be observed that it forms only a partial cover for the top open end (see Figure 7); the body portion of the spout is then folded along the line 35 to 20 stand at a right angle to the end 13, and its wings 22, 23 folded along the scored lines 45 and 46 to stand parallel with the sides 10 and 11, in which position they are shown in Figure 8, and when the body 21 of the 25 spout is fully folded its free margin extends to the free inner margin of the top part 20.

The top part 20 is then folded, along the line 33 to overlie the part 19, and the remaining top part 18 is folded along the line 27 to overlie the part 19, the parts 18, 19 and 20 all being relatively secured by gluing except for the sealing flap 24 with its wing 25.

33 This wing is then inserted in the gap 47 (see Figure 8) between the side 11 and the wing 22 of the pouring spout and the filled carton is ready for trade.

To open the carton, a sharp blade is passed 40 along the line 48, which is preferably a printed line, which frees the portion numbered 24 from the remainder of the top, the wing 25 is then withdrawn, the whole flap with its wing swung outwardly as shown 45 in Figures 7 and 8 which permits access to the pouring spout, which spout is then swung on the scored line 35 to the position shown in Figure 7 wherein its body 21 parallels the end 13 of the carton and its wings 50 stand at right angles to the body of the spout and parallel with the sides 10 and 11.

After each discharge the pouring spout may be extended into the carton and the top closed against the entrance of undesirable matter or the leakage of its contents 55 by the sealing flap 24.

What I claim:

1. A dispensing carton, consisting of a top composed of a number of elements which form part of the cover and an element constituting a full closure of the carton, one of said first-mentioned elements having wings to form a pouring spout, the full closure element being provided with a mark to indicate a line of cut, which mark is located to 60 register with the meeting line of said spout element, and the other first-mentioned elements.

2. A dispensing carton, consisting of a top composed of a number of elements which form part of the cover and an element constituting a full closure of the carton, one of said first-mentioned elements having wings to form a pouring spout, the full closure element being provided with a mark to 65 indicate a line of cut, which mark is located to register with the meeting line of said spout element, and the other first-mentioned elements, and the portion of said full closure flap overlying the spout element being adapted to form a closure for said spout element when in closed position.

3. A dispensing carton, consisting of a top composed of a number of elements which form part of the cover and an element constituting a full closure of the carton, one of said first-mentioned elements having wings to form a pouring spout, the full closure element being provided with a mark to indicate a line of cut, which mark is located to 80 register with the meeting line of said spout element, and the other first-mentioned elements, and the portion of said full closure flap overlying the spout element being adapted to form a closure for said spout element when in closed position, and having 85 means thereon for the securement thereof in closed position.

In testimony whereof I hereunto affix my signature.

THOMAS WALDRON.
